Application March 25, 1937, Serial No. 132,929
In Germany December 3, 1935

9 Claims. (Cl. 112—176)

The present invention relates to a new and improved sewing machine, more particularly to a sewing machine of the blind-stitch type by means of which a plurality of layers of material can be sewn together. The stitches baste one of the layers at a predetermined spacing, whereby the finished job appears to be hand-stitched, or for any other purposes such as, for example, are accomplished by the machines disclosed in the U. S. Patents No. 1,926,644 and No. 1,964,381.

An object of the present invention resides in the provision of improvements in sewing machines for making spaced blind stitches, particularly in the provision of means for improving the sewing together of layers of material of any thickness correctly, quickly, and reliably.

With sewing machines of the kind described in the U. S. Patent No. 1,926,644, sewing together of layers of material of equal or almost equal thickness only is possible. The reason for this is that, in said machine, the stroke of the device for bending the material to be sewn is always the same, whereas the part on which the material rests makes a stroke which is alternately long and short without variation, however, of the difference or the interval between the long and the short stroke.

A further disadvantage of the interval sewing machine of the kind disclosed in U. S. Patent No. 1,926,644 is that, for moving the support for the material upwards and downwards, comparatively large masses must be moved, whereby vibrations are caused which impair exactness and reliability of operation and reduce the operating speed.

It is an object of the present invention to provide means for varying the interval between the short and the long stroke of the support of the material to be sewn; this variation or adjustment can be made by the person operating the sewing machine, and no special expert is required for making the adjustment.

Adjustment of the difference between the long and short strokes is necessary when either two thick layers of cloth or two thin layers or layers of cloth of medium thickness or a thick and a thin material are to be sewn together in the interval. The difference between the strokes of the material carrier can be exactly adjusted to suit the thickness of the material to be worked, and a good interval seam can be created.

To accomplish the above stated objects, a machine as disclosed in the U. S. Patent No. 1,926,644 has been provided with means which will be described later on and which form part of the present invention.

Another object of this invention is to provide means for eliminating further disadvantages inherent to an interval stitching machine of the type disclosed in the U. S. Patent No. 1,926,644.

The movement of the material to be sewn together with the motions of the carrier of said material and of the device for bending the material annoys the operator and causes damage to the material to be worked. These disadvantages are particularly noticeable when thick and heavy material and pieces of great size are to be worked. The main disadvantage, however, is that in this case comparatively large masses are in motion which cause undesired vibrations which do not permit fast operation of the sewing machine. Whereas with the known interval sewing machines the device for bending the material, carries out a swinging motion of always the same amplitude and the material to be worked makes always the same stroke, the present invention has for its object the provision of means for varying the difference or the so-called interval of the strokes of the node forming element, whereby this variation can be carried out at will by the operator of the machine.

Due to the adjustability of the movements of the node forming element, cloths of equal thickness or of different thickness, for example, a very heavy and a very thin cloth as well as cloth of medium thickness can be sewn together with blind stitches in the interval. The adjustment of the difference of the strokes of the node forming element to suit variable thickness of the cloth to be worked is extremely easy and requires very little time.

In all cases, a correct, flexible, soft, and loose interval seam is created which is otherwise only possible with stitching by hand.

Interval sewing machines according to the present invention are particularly suitable for fitting the lining in coats and frocks in such a manner that the seam can be seen neither from the outside nor from the inside.

Further and other objects of the present invention will be hereinafter set forth in the accompanying specification and claims and shown in the drawings which, by way of illustration, show what I now consider to be the preferred embodiment of my invention.

In the drawings attached to the present specification, various modifications of the present invention are illustrated.

Fig. 25 is a sectional view of the device illustrated in Fig. 24 and taken along line 25—25 of that figure.

The invention is illustrated in connection with a blindstitch machine which is mainly standard in construction. This machine has a frame F, a main shaft 1, a drive pulley 2, and the usual hand-wheel 3. It is also provided with the usual pivoted work holder 4 which is pivotally connected at 5 to the frame F of the machine. The machine is also provided with the usual thread guide 6 having the usual spring 7 and the usual regulating member 8. The main shaft 1 actuates the feed dog and the looper and the needle by means of said standard connections which are shown in Figs. 1 and 2.

For example, the machine comprises a feed dog bar 9 which is connected to the main shaft by means of a suitable eccentric 10. Likewise, the

machine is provided with a looper 11 of standard construction which is connected to a looper bar 12, and this looper bar 12 is connected by means of a ball-bearing to the usual turnable yoke 14 which is pivotally connected to the frame of the machine at 15. The looper bar 12 is provided with the usual yoke 16 which is connected by means of the usual universal joint to the inclined projection 17 which extends from the collar 18 which turns in unison with the drive shaft. The needle N is mounted by means of a needle bar Na upon the usual shaft 20 which is suitably connected to the main drive shaft 1 so that the needle shaft 20 is caused to oscillate in the usual manner. The work-holder 4 is provided with the usual pair of pivoted fingers 80 and 81 on which the work is supported, and the work-holder is also provided with the usual finger 22 which is caused to turn up and down in order to form the bight in the layers of cloth. The fingers 80 and 81 have extensions 80b to which the tension springs 80a and 81a are connected. The members 80 and 81 are pivotally connected to the work-holder in the usual manner.

The machine has the usual presser foot 23. This presser foot 23 is fixed in the usual manner to the frame arm 24.

The work-holder 4 is automatically depressed at each alternate stroke of the needle or in any other desired ratio. The drive shaft 1 is located in a frame arm 25. It is to be understood that, when I refer to the work-holder, I refer to the support 4 which is shown in Fig. 4. When I specify the work-holder, I do not intend to refer merely to the rib 22 which forms the fold or bight in the material. The rib or finger 22 is always operated in the usual manner, so that it is adjusted or shifted in unison with the automatic shift of the member 4.

As shown in Fig. 5, the main drive shaft 1 has freely mounted thereon a collar or sleeve 26 which has an eccentric portion 26a and a concentric portion 26b. Although the parts 26a and 26b are integral, they may be considered as forming separate operating members. The eccentric member 26a has the usual eccentric strap 27 mounted thereon, and this strap 27 is integral with a lever 28.

As shown in Fig. 4, this lever 28 is pivotally connected at 29 to a member 30 which is clamped or otherwise suitably secured around the shaft 31 upon which the rib 22 is mounted, so that the rib 22 is caused to oscillate. Any other form of rib may be used to form the fold in the fabric in order to permit the formation of blind-strokes.

The concentric part 26b of the collar 26 has a gear 32 keyed thereto. One side of this gear 32 either has integral therewith or suitably connected thereto a ring 33. A pair of vertically movable arms 34 and 35 are provided which arms 60 have a rectangular, preferably square upper part. These arms 34 and 35 are also provided with openings through which the member 26b passes, and these openings are square and slightly greater than the sleeve 26b, so that the arms 34 and 35 65 can be vertically shifted with respect to the member 26b. The arm 34 has located therein a guide block 34a which fits upon the sleeve 26b, and the arm 35 is provided with an inner guide block 35a which fits upon the sleeve 26b. The guide blocks 34a and 35a also have outer peripheries which are rectangular and preferably square, and they have circular openings through which the sleeve 26b passes. The inner surfaces of arms 34 and 75

35 slide on the outer surfaces of guide blocks 34a and 35a.

As shown in Fig. 3, the eccentric member 26a abuts a portion of the internal surface of the frame arm 25. The assembly of the parts is maintained by the laterally projecting flange of the sleeve 26 and by means of a collar 36 which is clamped to the shaft 1 by means of a screw 37. The collar 36 is provided with a pair of lugs 38 and 38a which fit into corresponding depressions provided in the sleeve 26b, so that the sleeve 26b turns in unison with the shaft 1. Likewise, the gear 32 is also caused to turn in unison with the shaft 1 because the gear 32 is keyed to the sleeve 26b. When the shaft 1 turns, the guide blocks 34a and 35a do not turn in unison with the shaft 1, and the outer arms 34 and 35 likewise do not turn in unison with the shaft 1.

The gear 32 meshes with a fibre gear 39 which is suitably connected to a disk 40 by means of a nave 41a. The relative movement between said gears 32 and 39 is slight, so that they always remain in mesh.

As shown in Fig. 5, the edge of disk 40 abuts the adjacent edge of the member 33. As shown in Fig. 3, the arms 34 and 35 have their lower ends connected by means of a pin 41 which passes through an intermediate link member 42 which is represented in Figure 7.

30 Likewise, and as shown in Fig. 3, the arms 34 and 35 have a pivot member 43 on which the fibre gear 39 and the disk 40 are turnably mounted. The plate 40 is eccentrically mounted with respect to its pivot pin 43 and, since the smooth periphery of disk 40 contacts with the smooth periphery of the ring 33, the fibre gear 39 drives the disk 40 and causes up and down movement of the arms 34 and 35. The up and down movement of the arms 34 and 35 is guided by means 40 of the guide blocks 34a and 35a.

As is obvious from Figs. 7, 14, and 15, pin 41 serves for connecting the arms 34 and 35 with the prismatic part 82 which is adapted to slidably move within the slot 83 of the link member 42. Member 42 is provided with an extension 42' which serves to support the bolt 84. The latter carries a head 85 which is revolvably supported in between the arms 34 and 35 by means of bolt 86. Bolt 84 carries an adjustment nut 87 which, together with bolt 84, extends through a slot 88 outside of the frame F. 89 designates a washer and 90 a spring which is wound around bolt 84 and abuts with one end against the extension 42' and with its other end against the head 85 of bolt 84.

55 The link member 42 is pivotally connected at 43 to a horizontally movable member 44 and is also pivotally connected at 45 to an arm 46 which is pivotally connected by a pin 47 to the frame F of the machine. The member 46 is shaped like a fork, and the upper ends 144 of the member 46 straddle the regulating screw 47a and also straddle the block 48 which is threaded upon the screw 47a. The block 48 has lugs which abut the members 144. When this screw 47a is turned by means of the head 49, the block 48 is forced inwardly or outwardly, thus turning arm 46 and regulating the position of member 42 which also regulates the position of the member 44. Another adjustment of the position of member 44 can be accomplished by manipulation of the nut 87, whereby the arms 34 and 35 can be moved to the right or to the left against the action of the spring 90, whereby the position of the part 82 75 within slot 83 of member 42 is changed.

A pin 50 passes through the block 48 and this pin 50 is connected to the head 51 of the regulating device which is connected to the frame of the machine by means of suitable screws 52, so that the block 48 can move in and out but cannot turn.

The head 49 has a toothed wheel 53 connected thereto. A click 54 is pivotally mounted upon a screw 55 and this click has a tooth 56 which is held against the toothed wheel 53 by means of a tension spring 57. The tooth 56 also serves as the index for a scale which is marked upon the tapered end of the member 49.

The work-holder 4 is tilted in the upward direction by means of a tension spring 60, the inner end of which is connected to the frame of the machine as shown in Fig. 8. The outer end of the tension spring 60 is connected to an eye-member 61 which is pivotally connected at 62 to a threaded member 63 upon which a regulating head 64 is provided. Hence, the tension of the spring 60 tends to hold the work-holder 4 yieldingly in its upper position, and this upper position can be regulated by turning the member 64. An auxiliary adjustable stop 65 is provided in order to limit the upward tilting of the work-holder 4.

As shown in Fig. 8, the member 44 has a compression spring 67 mounted upon it, and the inner end of this compression spring 67 abuts a sleeve 69 which is adjustably mounted upon the member 44. The sleeve 69 is integral with a clamping collar 66 so that the member 69 can slide along and be clamped on member 44 in any desired position in order to regulate the compression of spring 67. When member 44 is pushed outwards by the arms 34 and 35, it is forced against the corresponding portion of the work-holder 4 so as to downwardly tilt the work-holder with reference to the pivot 5.

In this particular embodiment, the gears 39 and 32 have a two to one ratio so that the gear 39 turns once for every two revolutions of the gear 32. The gear 32 turns once with every complete oscillation of the needle. Hence, the work-holder 4 is depressed or tilted in the counterclockwise direction once for each two complete oscillations of the needle shaft. If any other desired ratio in the skipping of the layers of fabric is desired, the ratio between the gears 39 and 32 can be changed.

The arms 34 and 35 move downwardly in order to turn the member 42 with reference to the pivot 45 and to thereby actuate the member 44 outwardly. The machine is particularly designed for securing a hand-sewn effect upon a hem which has three layers A, B, and C. Every time a stitch is made, the thread is visible on the outside face of the layer A. In order to secure the imitation of hand-sewing, it is desirable to skip the markings by having the stitch skip the layer A in any predetermined manner.

Hence, the object of tilting the work-holder is to cause the needle to skip the layer A in any desired series as, for example, one to two, one to three etc.

For example, Fig. 10 shows the needle passing through the three layers of the hem, and Fig. 11 shows how the needle skips or misses the layer A.

The cloth is prevented from moving up too far under the action of the rib 22 by means of a finger 70 which is mounted upon a pivot pin 71b and which is forced downwards by means of a torsion spring 72. The pin 71b is mounted upon the extension 71 of an arm 71a.

Blind stitch sewing machines according to the present invention and having provisions for adjusting the so-called intervals produce loose, soft, and good looking seams which look as if they had been made by hand. The reason for this is that the lower layer need not be stitched into at every revolution but only at every other revolution.

In the embodiment of the present invention illustrated in Figs. 16 to 25, inclusive, 101 designates the frame of the machine, 102 the driving pulley, and 103 the main drive shaft. To the shaft 103, an eccentric 104 is connected comprising a lever 105 to which the main drive rod 106 is linked. To rod 106, the oscillating shaft 112 is linked by means of levers 107, 108, 109, 110, and 111. An intermediary lever 114 connected with rod 112 transmits the movements of rod 112 to the device for bending the cloth, the node forming element 115. As is more clearly shown in Fig. 17, the latter moves up and down in the slide 116. 117 is a stationary pressing plate which has an opening through which element 115 extends before abutting the layer 118 and also bending up layer 119 which rests on layer 118. Needle 120, which is guided by the stitch plate 121, enters layer 119 as shown in Figs. 16 and 17 at a revolution of the main 103 at which the layers of cloth are lifted by the node forming element 115. At the next following complete revolution of main shaft 103, needle 120 enters layer 118 because node forming element 115 is then lifted further upwards. Pressing plate 117 is movably connected with the slide 116, whereas needle 120 and stitch plate 121 are connected with the head of the frame of the machine in a manner which is not shown because this does not form part of the present invention, and is well known in the art. To the bolt 105' which links lever 105 to lever 106, a guide lever 122 is movably connected as is particularly shown in Fig. 20. As is obvious from Fig. 20 lever 122 is linked to link-pin 105' which is common to levers 105 and 106 so that the axis of pin 105' is guided on an arc which arc, at normal stroke of the eccentric 104, is an almost straight, vertical line. Lever 123 is movably connected to link bolt 107' which interconnects levers 107 and 108. Lever 123 guides the end of lever 107 on a substantially straight path. To lever 106, control lever 124 is movably connected which is driven by means of shaft 103 to which it is operatively connected by means of the tooth wheels 125, 126, and 127. As is shown in Fig. 21, wheel 127 is mounted to the short shaft 128 which carries at its front side a slide 129 which, by means of a crank pin 130 and a cross head 131 which is reciprocatingly moved in the slide 132 by means of said pin 130, causes an oscillating movement of lever 124. The shaft stump 128, tooth wheel 127, slide 129, and pin 130 together form a crank drive, the active radius of which can be varied by movement of pin 130 by means of slide 129 from the position in which the axis of pin 130 coincides with the axis of shaft 128 into a position in which pin 130 is furtherest away from shaft 128. Such movement is carried out by rotating wheel 133 which is rotatable about the shaft 128 and comprises an arcuate slot 133'. Slot 133' abuttingly cooperates with bolt 134 which is pushed toward or from shaft 128 when wheel 133 and with it slot 133' is rotated. Bolt 134 thereby moves in the slot 135 and, being connected with slide 129, also moves said slide in a reciprocating manner. The distance of pin 130 from shaft 128 can be set by tightening nut 136, which nut must be loosened before adjusting

the position of the crank pin. Pin 130 is revolvably connected with member 137 which is slidable in the slide frame 131 and forms a cross head therewith which is reciprocatingly movable in slide frame 132. The circular movement of crank pin 130 is thus transmitted into a reciprocating motion of part 131 and the control rod 124 connected thereto.

As is obvious from Figs. 18 to 21, inclusive, the control mechanism protrudes from the frame 101 of the machine and is housed in a casing 138 having a cover 138', which casing is mounted to the frame and is easily accessible.

In the machine according to Figs. 16 to 21, inclusive, the fulcrum of lever 124 is moved in a straight line at every other revolution of the main shaft of the sewing machine as far to the left as it is moved to the right at every fourth revolution of the main shaft.

In the machine shown in Figs. 22 and 23, the operation is simplified; in this case the fulcrum of lever 124 swings on a circular path and an only approximately straight motion is created. This, however, is sufficient for practical purposes. In the machine according to Figs. 22 and 23, the slide 132 of the machine according to Figs. 20 and 21 is replaced by the pendulum 132' which swings about fulcrum 122' and which imparts a reciprocating motion to control lever 124. Crank pin 130 is guided in slide 131' which is directly connected with pendulum 132'. The tooth wheel 127 is driven by a tooth wheel 126 which is operated by a tooth wheel which is connected to the main drive shaft 103 and corresponds to wheel 125 in Fig. 20. The speed ratio of the transmission from shaft 103 to shaft 128 is one to four. Lever 106 is in its medium position at the first revolution of the machine and in the moment in which the eccentric 104 is in its lower dead center position. At this position of lever 106, the node forming element reaches its normal elevation. At the next following, i. e., second revolution of the main shaft 103, lever 106 reaches its left interval position in which eccentric 104 is again in lower dead center position. The node forming element then rises to interval position only. At the next following revolution, lever 106 swings into right interval position.

In the embodiment of my invention illustrated in Figs. 24 and 25, the ratio of the speed transmission between tooth wheel 125', which corresponds to wheel 125 in Figs. 20 to 23, and wheel 127 which corresponds to wheel 127 in Figures 20 to 23 is only one to two. By means of control 124', lever 106 is moved from the normal medium position into interval position at left and back to medium position and again to left interval position. Therefore, the interval cannot be changed within such a wide range as is the case in the machine shown in Figs. 20 to 23 but within a limited range only. The modification of the present invention illustrated in Figures 24 and 25 is further simplified in that a slide 132 as in Figure 20 or a swing member 132' as per Figure 22 is omitted.

In all the embodiments of the present invention described in this specification, the interval is changed by enlargement or reduction of the crank radius of the crank pin 130 with respect to shaft 128, whereby the degree to which lever 106 is swung out of its medium position is changed. Thereby, the adjustment of the drive of the device for bending the material to be

sewn is done in accordance with the thickness of said material.

While I believe the above described embodiments of my invention to be preferred embodiments, I wish it to be understood that I do not desire to be limited to the exact details of design and construction shown and described, for obvious modifications will occur to a person skilled in the art.

10. What I claim is:

1. A blind-stitch sewing machine comprising a node forming element for forming a bight in the material to be sewn, driving means connected with said element and adapted to impart a reciprocating motion to said element, said driving means comprising a link-lever, a control lever linked to a point of said link-lever which point is intermediary the two ends of said link-lever and which forms a fulcrum about which said link-lever swings, operating means connected with said control lever for imparting a substantially reciprocating motion to said control lever, adjusting means connected with said operating means for changing the stroke of the reciprocating motion of said control lever and thereby changing the position of said fulcrum and the stroke of the reciprocating motion of said node forming element.

2. A blind-stitch sewing machine comprising a node forming element for forming a bight in the materials to be sewn, driving means connected with said element and adapted to impart a reciprocating motion to said element, said driving means comprising a link-lever which moves substantially reciprocatingly in substantially the direction of its longitudinal extension, a control lever linked with one end to a fulcrum of said link-lever which fulcrum is situated intermediary the two ends of said link-lever, a cross head linked to the other end of said control lever, said cross head being adapted to reciprocatingly move in a direction which is substantially perpendicular to the direction of the reciprocating motion of said link-lever.

3. A blind-stitch sewing machine comprising a main drive shaft, a node forming element for forming a bight in the materials to be sewn, driving means connected with said element and adapted to impart a swinging motion to said element, said driving means comprising a link-lever which is adapted to move substantially reciprocatingly in substantially the direction of its longitudinal extension, said link-lever comprising a fulcrum which is situated intermediary the two ends of said link-lever, a control lever linked with one end to said fulcrum, a cross head linked to the other end of said control lever, a gear-wheel having a crank-pin connected thereto which pin is movably connected with said cross head and which reciprocatingly moves said cross head in a direction which is substantially perpendicular to the direction of the reciprocating motion of said link-lever, and a train of toothed wheels connecting said gear-wheel and said main drive shaft.

4. A blind-stitch sewing machine comprising a main drive shaft, a node forming element for forming a bight in the material to be sewn, driving means connected with said element and adapted to impart a swinging motion to said element, said driving means comprising a link-lever which is adapted to move substantially reciprocatingly in substantially the direction of its longitudinal extension, said link-lever comprising a fulcrum which is situated intermediary the

two ends of said link-lever, a control lever linked with one end to said fulcrum, a cross head linked to the other end of said control lever, a gear-wheel having a crank-pin connected thereto which pin is movably connected with said cross head and which reciprocatingly moves said cross head in a direction which is substantially perpendicular to the direction of the reciprocating motion of said link-lever, and a train of toothed wheels connecting said gear-wheel and said main drive shaft, said train of wheels effecting a speed reduction of said gear-wheel with respect to the speed of said main drive shaft.

5. A blind-stitch sewing machine comprising a main drive shaft, a node forming element for forming a bight in the material to be sewn, driving means connected with said element and adapted to impart a swinging motion to said element, said driving means comprising a link-lever which is adapted to move substantially reciprocatingly in substantially the direction of its longitudinal extension, said link-lever comprising a fulcrum which is situated intermediary the two ends of said link-lever, a control lever linked with one end to said fulcrum, a cross head linked to the other end of said control lever, a gear-wheel having a crank-pin connected thereto, which pin is movably connected with said cross head and which reciprocatingly moves said cross head in a direction which is substantially perpendicular to the direction of the reciprocating motion of said link-lever, and a train of toothed wheels connecting said gear-wheel and said main drive shaft, said train of wheels effecting a speed reduction of one to four of said gear-wheel with respect to the speed of said main drive shaft.

6. A blind-stitch sewing machine comprising a main drive shaft, a node forming element for forming a bight in the materials to be sewn, driving means connecting said main drive shaft and said element for imparting a swinging motion thereto and comprising a main link-lever adapted to reciprocatingly move substantially in the direction of its longitudinal axis, a parallel guide means comprising a member adapted to reciprocatingly move substantially parallel to the longitudinal axis of said main link-lever, said main link-lever having two ends one of which is movably connected with said parallel guide means, another link-lever also having two ends one of which is movably connected with that end of said main link-lever which is not connected with said guide means, the other end of said other link-lever being movably connected with said parallel guide means, whereby one end of said main link-lever and one end of said other link-lever are guided to move substantially parallel to the longitudinal axis of said main link-lever.

7. A blind-stitch sewing machine comprising a frame, a node forming element for forming a bight in the materials to be sewn, driving means connected with said element and adapted to impart a reciprocating motion to said element, said driving means comprising a link-lever which moves substantially reciprocatingly in substantially the direction of its longitudinal extension, a control lever movably linked with one end to said link-lever at a point which is situated intermediary the two ends of said link-lever, an eccentric having a disc and a rod, said disc containing a cross head having a pin which is movably connected to the other end of said control lever, said rod being movably connected to said frame and being adapted to swing in a direction which is substantially perpendicular to the direc-

tion of the reciprocating motion of said link-lever.

8. A blind-stitch sewing machine comprising a main drive shaft, a node forming element for forming a bight in the materials to be sewn, driving means connected with said element and adapted to impart a swinging motion to said element, said driving means comprising a link-lever which is adapted to move substantially reciprocatingly in substantially the direction of its longitudinal extension, said link-lever comprising a fulcrum which is situated intermediary the two ends of said link-lever, a control lever linked with one end to said fulcrum, a slide carrying a pin which is movably connected with the other end of said control lever, a gear-wheel having a guide for carrying said slide, whereby, upon rotation of said gear-wheel, said control lever is moved in a direction which is substantially perpendicular to the direction of the reciprocating motion of said link-lever, and a train of toothed wheels connecting said gear-wheel and said main drive shaft.
9. A blind-stitch sewing machine comprising

a main drive shaft, a node forming element for forming a bight in the materials to be sewn, driving means connected with said element and adapted to impart a swinging motion to said element, said driving means comprising a link-lever which is adapted to move substantially reciprocatingly in substantially the direction of its longitudinal extension, said link-lever comprising a fulcrum which is situated intermediary the two ends of said link-lever, a control lever linked with one end to said fulcrum, a slide carrying a pin which is movably connected with the other end of said control lever, a gear-wheel having a guide for carrying said slide, whereby, upon rotation of said gear-wheel, said control lever is moved in a direction which is substantially perpendicular to the direction of the reciprocating motion of said link-lever, and a train of toothed wheels connecting said gear-wheel and said main drive shaft.

OSKAR STROBEL.
